UNITED STATES PATENT OFFICE.

WILLIAM M. RANDOLPH, OF PITTSBURG, PENNSYLVANIA.

DESIGN FOR A CIGAR-PROTECTOR.

SPECIFICATION forming part of Design No. 33,494, dated November 6, 1900.

Application filed September 20, 1900. Serial No. 30,630. Term of patent 7 years.

To all whom it may concern:

Be it known that I, WILLIAM M. RANDOLPH, a resident of Pittsburg, in the county of Allegheny and State of Pennsylvania, have invented a new and original Design for Cigar-Protectors; and I do hereby declare the following to be a full, clear, and exact description thereof, reference being had to the accompanying drawings, in which—

10 Figure 1 is an outside plan view of the cigar-protector, showing my new design. Fig. 2 is an inside plan view of the same; and Fig. 3 is a cross-section thereof on the line 2-2, Fig. 1.

As illustrated in the drawings, the leading 15 or essential feature of my design consists of a plate having flutes or corrugations formed therein of concavo-convex shape, so as to form pockets. The ends of each flute or corrugation are rounded or curved on each side, 20 and the inner curves terminate in an apex or point. Flanged lips are also formed on each side of the plate.

1 represents the plate, and 2 the concavo-

convex flutes or corrugations, which form the pockets 3 on each side of the plate 1. 4 represents the ends of the plate 1, and the flutes or corrugations 2, which terminate at the ends 4, are rounded or curved at each side, thereof, as at 5. The inner curves 5 terminate in an apex or point 6, and the outer curves 5 terminate in a flanged lip 7, formed on each side 1' of the plate 1. 25 30

Having described my invention, what I claim as new, and desire to secure by Letters Patent, is—

The design for a cigar-protector, substantially as herein shown and described.

In testimony that I claim the invention above set forth I affix my signature, in presence of two witnesses, at Pittsburg, in the 40 county of Allegheny and State of Pennsylvania, this 19th day of September, 1900.

WILLIAM M. RANDOLPH.
